UNITED STATES PATENT OFFICE.

CHARLES H. COWAN, OF NEW ROCHELLE, NEW YORK, ASSIGNOR TO COLUMBIA PHONOGRAPH COMPANY, INC., OF BRIDGEPORT, CONNECTICUT, A CORPORATION OF NEW YORK.

DESIGN FOR A CABINET FOR SOUND-REPRODUCING MECHANISM.

Application filed November 11, 1926. Serial No. 19,683. Term of patent 7 years.

To all whom it may concern:

Be it known that I, CHARLES H. COWAN, a citizen of the United States, residing at New Rochelle, in the county of Westchester and State of New York, have invented a new, original, and ornamental Design for Cabinet for Sound-Reproducing Mechanism (Model No. 601), of which the following is a specification, reference being had to the accompanying drawing, forming a part thereof.

The figure is a perspective view of a cabinet, showing my new design.

I claim:

The ornamental design for a cabinet for sound-reproducing mechanism, substantially as shown.

CHARLES H. COWAN.
